UNITED STATES PATENT OFFICE.

CHARLES S. BARRETT, OF DENVER, COLORADO.

AEROPLANE.

1,402,205.

Specification of Letters Patent. Patented Jan. 3, 1922.

Application filed March 1, 1920. Serial No. 362,298.

To all whom it may concern:

Be it known that I, CHARLES S. BARRETT, a citizen of the United States, residing at 1007 15th St., Denver, in the county of Denver and State of Colorado, have invented 5 certain new and useful Improvements in Aeroplanes, of which the following is a specification.

My invention relates to an improvement 10 in aeroplanes and has for its primary object the construction of a simple, durable and inexpensive device capable of rising vertically from the ground.

Still another object of my invention is to 15 provide a device of the class described with ability to rise vertically, and in the case of mishap to machinery the rising propeller will seal itself by the release of a rope and act as a parachute.

20 Still another object of my invention is to provide an aeroplane with a propeller for vertical rising, and the said propeller being adjustable with regard to the angle by which it cuts the air, having a device which 25 will hold the blades in angular position should any mishap occur in the machinery or the driving device or the means by which the propeller is held at an angle. The said propellers will automatically flatten out and 30 form a parachute.

These and such other objects as may be here-in-after enumerated are attained by the novel construction, combination and arrangement of parts to be hereinafter specifically 35 referred to and claimed.

Though I show one particular embodiment of my invention, I wish to be limited only to the scope of my claims as it will readily be seen that mere mechanical details may be changed without going beyond the limitation of my claims.

Reference will now be had to the accompanying drawings forming a part of this application. Figure (1) is a plan view 45 showing the vertical propeller frame work, horizontal propeller, and rudder. Figure (2) is an enlarged view showing the mechanism controlling the angle at which the propeller is to be operated. This view is 50 broken and is an isometric view. Figure (3) is a side elevation of the aeroplane, on section 3—3 showing driving mechanism and other parts which can not be clearly shown otherwise.

55 Throughout the following detailed description and on these several figures of

drawings similar parts are referred to by like reference characters. Numerals (1) are a plurality of propeller blades made up of cloth and stretched over a propeller frame (2) which is covered by a fabric 2^a which rotates about the shaft (3) which acts as a shift only with regard to the angle. The propeller blades are set. The nigger head (4) revolves about a shaft (5). The nigger head (4) is driven by a rope (6) which travels over a pair of shift wheels (7), located in the main frame (8) of the propeller mechanism. The rope (6) receives its energy from a drive shaft (9) which may be 60 connected to an energy producing mechanism such as a gasolene motor or an electric motor or the like.

At one end of each of the propeller blades (2) is a shift pin (10), which is revolvably 75 fixed in a lug (11), and the lug (11) being rigidly fixed in an angle iron hoop (12) and at the opposite end of the propeller frame (2) is another shift pin (13) which is revolvably held by lug (14), which in 80 turn is rigidly fixed to an angle iron hoop (15). It will be seen that by a pull on rope (16) exercising its energy or lever (18) that, through a dog (19) the power exerted on (16) will draw hoop (15) away from 85 hoop (12), thereby regulating the angle at which these propeller blades are set at the choice of the operator. Lever (18) is pivoted on a bolt or pin (20) which is rigidly fixed to frame (8). From this description 90 it will also be seen that should some mishap occur in the machinery or the rope, or cable should break the descending of the plane would force the propeller blades to close up and form a form of parachute, as the upper 95 hoop (12) could not raise by the pressure of the wind against a roller (21) which is revolvably fixed in place on the stationary frame (8) by the propeller blades being pivoted in themselves off center on their shafts 100 (3) the pressure would raise the end connected to the hoop (15). This would move up close enough to form the outer rim of a parachute and retard the descending of the plane. (22) is a propeller which causes 105 the horizontal movement of the plane and is joined in the frame (8) by conveniently placed bearings (23) and driven by a shaft (25) which, through a sheave at one end (26) receives its energy from a rope or cable 110 (27). This cable or rope receives its energy from a drive shaft (28) which in return is

driven by some form of motor power similar to that driving the drive at (9) and which is located in the body of the plane (29). (30) are the truss rods which are used to 5 stiffen the frame, and (31) are the brace rods which hold the frame in its proper position. (32) is the rudder of usual type and controlled by mechanism of convenient design. (33) are roller bearings set in nigger head (4) which revolve about the strut shaft (34) which is a part of the frame work (8) 10 and the body of the plane (29).

Having thus described my invention or what I claim is new and desire to protect 15 by Letters Patent is:

In an aeroplane, of the class described a propeller for horizontal motion of the aeroplane and controllable propeller for vertical motion, this propeller consisting of a plu-

rality of blades each rotatably mounted on 20 a shaft, the inner end of the shaft rotatably mounted on a spindle of a vertical shaft, the outer end of the shaft rigidly affixed to propeller blade frame 2, two outer rim rings, means for attaching said frame 25 to said outer rim rings, and means for governing the distance of separation of said rim rings, to govern the set or angle of the blades and a means for driving the vertical shaft which imparts the motion of the propeller, 30 and a frame of suitable construction for holding all the above said means in place.

In testimony whereof, I have affixed my signature in the presence of two witnesses.

CHARLES S. BARRETT
